UNITED STATES PATENT OFFICE.

WILLIAM R. CLEARY, OF PHILADELPHIA, PENNSYLVANIA.

STEAM CHAMBER FOR TANK CARS.

Application filed November 25, 1924. Serial No. 752,262.

This invention relates to tank railway cars, and more particularly to a steam chamber for attachment to the undersurface of the tank of the car for the purpose of heating the material contained within the tank car.

The principal object of the invention is to provide a steam heating chamber which is positioned exteriorly of the tank on a railway car and which extends along the under- 10 surface thereof for eliminating many of the disadvantages and expense incurred with the use of coils in that liability of rupturing the heating coils is eliminated, and further provides the advantage of repairing the 15 heating chamber when necessary from the exterior of the tank.

A further object of the invention is to provide a steam or heating chamber which will afford a relatively great heating surface 20 to the tank, and which will provide uniform heating throughout the entire length of the tank car and by placing the heating chamber beneath the tank. The natural radiation of the heat which is 25 upward will travel through the tank and the material therein for melting the said material and keep it in a liquid or semi-liquid state; and furthermore, by placing the heating chamber exteriorly of the tank, 30 the formation of residue about the heating chamber will be eliminated.

A further object of the invention is the provision of a steam heating chamber in combination with a tank car wherein the 35 quantity of the steam charge or charges will be reduced to a minimum, in that the condensation except the exhaust, will be allowed to remain in the chamber until the car is unloaded, thereby permitting the maintaining 40 of a uniform temperature over the entire length of the car with the use of a relatively small quantity of steam.

Other objects of the invention will appear in the following detail description and in 45 the accompanying drawings wherein:

Figure 1—is a perspective view of a tank car, showing the improved heating chamber applied thereto.

Figure 2—is a top plan of the heating 50 chamber illustrating the braces and their manner of arrangement.

Figure 3—is a detail cross section through the car.

Figure 4—is an enlarged detail view of 55 the center or tank contact drain outlet and reducing nipples and cap therefor.

Referring more particularly to the drawings, the improved steam or heating chamber 1 is shown as attached to the undersurface of the tank 2 of a tank car 3 of any approved type. The steam or heating chamber 1 extends throughout the entire length of the tank 2 and is attached thereto along its edges in any suitable manner, such as by rivets 4, as clearly shown in Figure 3 of the drawings, so as to provide a fluid-tight connection between the outer plate 5 which forms the steam chamber in conjunction with the surface of the tank. To prevent buckling of the heating chamber and to provide 70 sufficient support for the weight of the car, the outer or bottom plate 5 is securely braced to the bottom of the shell of the tank, by means of a plurality of brace bars 6, 7 and 8, which extend longitudinally of the steam 75 chamber and are securely riveted to the shell of the tank by rivets 9 which extend through the tank, the respective brace bars, and the outer or bottom plate of the steam chamber. As clearly shown in Figure 2 of the drawings, the center brace bars 8 are placed at 80 relatively great distances apart so as to permit accommodation of the various outlets and inlets for the chamber while the bars 7 which are relatively heavy, are placed closer 85 together, and nearer to the longitudinal center of the steam chamber to provide sufficient bracing for the center portion, and it will also be noted that the respective brace bars have their ends arranged to provide a 90 plurality or a net work of channels through which the steam or heated element may circulate over the entire length of the car for heating the tank to heat or melt the contents thereof.

The chamber has steam inlets or outlets 10 and 11 respectively, which are equipped with reducing sockets 12 and nipples 13, as clearly shown in Figure 3 of the drawings, and these openings are disposed in proper position relative to the transverse center of the chamber and are used for permitting steam to enter the chamber or for draining the steam from the chamber when not in use.

In addition to the steam inlets or outlets, four flanged openings 14 are provided at proper spaces and these flanged openings 14 may be fitted with valves at the time of the unloading of the tank and used to draw off the exhaust steam which will accumulate 110 while heating the liquid in the car preparatory to unloading.

It is, of course, to be understood, that the invention may be constructed in various other manners and the parts associated in different relations, and therefore, I do not desire to be limited in any manner, except as set forth in the claim hereunto appended.

What I claim is:

In a railway tank car, a rectangular plate secured to the underside thereof about its side and end edges and formed to provide a fluid-tight chamber between said plate and the outer bottom surface of said tank, a plurality of relatively short rectangular spacing bars equally and transversely disposed parallel to the side edges of said plate and adjacent each end of said chamber, a steam inlet and steam outlet port provided

centrally in said plate on the longitudinal center line thereof, a tank drain nipple extending through from the enclosed underside of said tank through and outwardly of said plate and centrally between said inlet and outlet ports, a plurality of short rectangular spacing bars secured to said plate and about the said inlet and outlet ports and tank drain nipple in a substantially circular manner, and parallel with said first named bars, said spacing bars adapted to provide a uniformly spaced chamber between said tank and plate throughout the length of said chamber.

In testimony whereof I affix my signature.

WILLIAM R. CLEARY.
